H. F. STARRETT,
DIRECTORY FRAME,
APPLICATION FILED JUNE 6, 1919.

Patented Feb. 1, 1921.

Fig. 1

Fig. 2

UNITED STATES PATENT OFFICE.

HENRY F. STARRETT, OF CHICAGO, ILLINOIS, ASSIGNOR TO STARRETT MANUFACTURING COMPANY, OF CHICAGO, ILLINOIS, A CORPORATION OF ILLINOIS.

DIRECTORY-FRAME.

1,366,968.

Specification of Letters Patent.

Patented Feb. 1, 1921.

Application filed June 6, 1919. Serial No. 302,157.

To all whom it may concern:

Be it known that I, HENRY F. STARRETT, a citizen of the United States, residing at Chicago, in the county of Cook and State of Illinois, have invented new and useful Improvements in Directory-Frames, of which the following is a full, clear, concise, and exact description, reference being had to the accompanying drawing, forming a part of this specification.

This invention relates to directory frames which may be used for any of a large variety of purposes, such as hotel room or elevator directories, and more especially as a directory for circuit designations and diagrams used in connection with panel boards.

One of the objects of this invention consists in the construction of an improved form of directory frame, which is both simple and substantial, and which is adapted to be cheaply and quickly mounted in position.

Another object comprises the production of an improved directory frame consisting of a substantially rough and cheaply constructed base plate which is adapted to be mounted in position independently of the transparent means and the cover plate associated therewith when in actual use, and in which the finished cover plate is removably secured to the base plate and functions to hold the transparent means and directory designation in place and to likewise give to the complete frame a finished appearance.

A further object consists in the production of an improved directory frame which can be quickly and readily disassembled to make necessary changes in the directory card designations.

Other objects of this invention will become apparent from the following description and the appended claims.

For the purpose of description, a preferred form of directory frame is illustrated in the accompanying drawings in which—

Figure 1 is a front view of the frame completely assembled;

Fig. 2 is a rear view of the frame completely assembled, and

Fig. 3 is a section taken on the plane, as indicated by the line 3—3 of Fig. 2 looking in the direction of the arrows.

As illustrated in the drawings, the directory frame comprises a base plate 8 which is preferably constructed of sheet metal. In the preferred embodiment, this base plate 8 is formed out of a rectangular sheet of metal with the corners of the rectangle cut away to reduce complications in the forming operation. Obviously any other shape of plate could be readily used. The base plate 8 is formed in a suitable press into a dished shape, each lateral edge being fitted with the upwardly extending flange 9 and the outwardly extending flange 10. Each of these flanges is perforated at substantially its middle point 11, these perforations being threaded to receive screws such as 12 for securing the cover plate frame 14 to the flanges 10 of the dished base plate.

The base plate 8 is also perforated at 15' and 16', these perforations being countersunk and adapted to receive suitable flat headed screws for mounting the base plate 8 to a suitable support such as a wall or door. The perforations 15' and 16' are used for the mounting of the base plate when the said plate is to be installed in places where the screw mounting is the most convenient form which can be utilized. When the directory frame is to be used in connection with panel board boxes in which the directory frame is mounted on the box at the factory where the panel board box is constructed, the base is preferably secured to the panel board cover by electrowelding the base plate direct to the cover of the box. Obviously any suitable means for mounting the base plate to its respective mounting support can be utilized.

Fitted within the dished plate 8 is a suitable card designation 15, above which is placed any transparent means 16, preferably glass or celluloid. The designation card 15, together with glass plate 16, are held in place in the dished base plate 8 by means of the cover plate frame 14. This cover plate 14 preferably consists of a sheet metal stamping, the cover frame being preferably fitted with a continuous peripheral flange 18 in the stamping or forming operation. This flange 18 is made sufficiently long so that it will practically contact with the mounting surface on which the base plate 8 is mounted when the cover plate is held in position on the base plate 8 by means of the

screws 12. The flange 18, therefore, functions to obscure the rough base plate 8 and thus gives to the completely assembled directory frame a pleasing and very slight appearance.

The mounting screws 12, which secure the cover plate frame to the base plate 8, are fitted through apertures in the cover plate frame which align with the threaded apertures 11 in the base plate 8. Obviously any other convenient means for securing the cover plate frame 14 to the base plate 8 might be used.

The base plate 8 is fitted with flanges 9 and 10 and given the dished form so it will perform the dual function of retaining the designation cards 15 and 16 within the enclosure formed by the bottom of the plate 8 and the upwardly extending flanges 9 and 20 so that the flanges 10 will be sufficiently removed from the mounting base to permit the ready insertion of the screws 12, which secure the cover plate frame 14 to the base plate 8.

Fig. 1 illustrates a designation card for a panel board, such as might be used in connection with a panel box and board in use in a hotel. Thus in this figure five circuits are indicated which show that five circuits 30 terminate in the particular panel board, these circuits supplying respectively the lobby, dining room, grill room, kitchen and mezzanine floor, as indicated.

It will now be evident from the foregoing description that a directory frame constructed in accordance with the teachings of this invention may be installed either completely or partially, depending upon service demands. Thus if it is known that directory 40 designation will be ultimately required, the base plate 8 can be conveniently installed when the rough construction work is being done, and the remainder of the directory frame will not have to be installed until the 45 directory designation is actually required. In this instance, the base plate 8 is secured and mounted in the position in which it is ultimately desired to place the directory designation.

Thus for example in a panel board and panel box, the base plate would be secured to the door of the panel box at the time that the box was being constructed and then if thereafter circuit designation or diagrams 55 are required, it is merely necessary to assemble the cover plate with the associated transparent means 16 and a suitable designation card. Likewise, due to the simplicity of the construction and the ease with which 60 the frame can be assembled and disassem-

bled, changes in directory designation can be very easily and rapidly performed.

Obviously the invention is not limited to the specific embodiment thereof herein illustrated and described, but is capable of many 65 variations and other applications within its spirit and scope as pointed out in the appended claims.

Having thus described my invention, what I claim as new and desire to secure by Letters Patent is:

1. In a device of the character described, in combination, a base plate fitted with a plurality of upwardly and outwardly extending flanges, a cover plate frame for said base plate having a downwardly extending peripheral flange, a transparent means positioned in said base plate inside of said upwardly extending flange, means removably interconnecting the cover plate to the outwardly extending flanges of said base plate, the peripheral flange of the cover plate substantially obscuring the lateral edges of the base plate and serving to hold said transparent means in position when the base and cover plates are interconnected in assembled relationship.

2. In a device of the character described, a dished base plate, a flange associated with each side of said plate, the said flange carrying threaded apertures, a cover plate frame, a downwardly extending continuous peripheral flange associated with said cover plate, said frame being fitted with perforations, a transparent means, and securing means 95 adapted to interconnect said cover plate and base plate in the aligned perforations of said cover plate and base plate, whereby the transparent means will be positioned in said dished base plate and the dished base plate 100 will be obscured by the continuous peripheral flange of the cover plate.

3. A new article of manufacture comprising in combination an unfinished base plate adapted to be secured to a mounting surface, said base plate being dished and fitted with a plurality of lateral flanges, a transparent means positioned in said dished plate, and a finished cover plate frame fitted with a peripheral flange, the said cover plate frame being adapted to maintain said transparent means in position in said plate, and being removably secured to the lateral flanges of said base plate, the flange of said cover plate extending over the lateral edges 115 of said base plate to obscure the same.

In witness whereof I have hereunto subscribed my name.

HENRY F. STARRETT.
